UNITED STATES PATENT OFFICE.

ALFRED BERNEY, OF BOSTON, MASSACHUSETTS, ASSIGNOR TO THE GLOBE COMPANY, OF HARTFORD, CONNECTICUT.

SMOKE-CONSUMING FURNACE.

SPECIFICATION forming part of Letters Patent No. 248,007, dated October 11, 1881.
Application filed March 22, 1881. (No model.)

To all whom it may concern:

Be it known that I, ALFRED BERNEY, a citizen of the United States, residing at the city of Boston, in the county of Suffolk and State of Massachusetts, have invented certain new and useful Improvements in Smoke-Consuming Furnaces; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to furnaces in which hot air and steam are supplied to the fuel to assist in its combustion; and the object is to prevent the chilling of the fire, and also to prevent smoke and gases from escaping, but to consume them 20 with the fuel.

The invention consists in forming at the rear of the furnace a lining connected with a diaphragm of fire-brick or other refractory material, which retains the heat and imparts it to 25 the air and products of combustion, and thereby assists in heating the air and consuming the fuel. In said lining are arranged a number of vertical perforations connected to a horizontal opening in the diaphragm and communicating 30 with one or both sides or the rear of the furnace with openings, into which steam-jet pipes protrude and form jets by which air is drawn or forced in, and after mingling with the air, which has been now highly heated, under the grate-bars and into the fire on the grate, all of which 35 will be more fully described hereinafter.

In the drawings, Figure I is a longitudinal vertical section of a furnace with my improvements attached. Fig. II is a cross-section of 40 the same on line x x.

In the drawings, A is the shell of the boiler, and B represents the furnace, connected with the flues C in the ordinary manner. In the furnace are arranged the grate-bars D, and below them is the ash-pit E, which is provided 45 with dampers or doors e, to be closed when the jet is on. At the rear side of this furnace is arranged a lining, F, extending at its upper side and connected to a diaphragm, G. This lining 50 and diaphragm are made of fire-brick or other

refractory material, and is provided with a number of vertical perforations, f, opening into the ash-pit below the grate-bars. These perforations connect with a horizontal or inclined opening, g, in the diaphragm. Into this opening one or more openings, on one or both sides of the furnace, lead by a thimble, h, through which a steam-jet pipe, i, provided with suitable stop-cocks or valves, protrudes, and by which air is drawn in and forced through the 55 perforations into the ash-pit.

If desired, one or more openings, k, may be arranged through the front water-legs of the furnace, and into them one or more steam-jets, l, may protrude to draw in air and force it with 60 the steam into the ash-pit. One or both of these steam-jets may be used at the same time, and, if desired, perforations may be made into the furnace through the lining, as shown at m, by which hot air and gases may be drawn from 65 the furnace and mingled with fresh atmospheric air and be forced into the ash-pit, thus causing a reverberatory action of air and steam, by which the smoke and gases will be entirely 70 consumed. The air in passing through the lining, which is very hot, becomes highly heated and assists in decomposing the steam, which 75 becomes highly superheated.

If desired, the steam-jet l may be bent downward, as shown by the dotted lines, to draw in 80 hot air from the furnace as well as from the atmospheric air.

I am aware that air and steam have been injected into the furnaces through perforated diaphragms and linings, but upon the upper 85 surface of the fuel, by which the fire is damped and lessened in intensity, and if strong enough may be extinguished. I am also aware that cold air has been admitted under the grate from the ash-pit; but this has a tendency to 90 chill or cool the fires. I therefore do not claim any such devices; but,

Having thus described my invention, what I claim as new is—

1. In a furnace, a lining constructed of refractory material and provided with a series of vertical openings connected to one or more openings in an inclined diaphragm, and one or more steam-jets for forcing hot air and steam into the ash-pit, substantially as specified. 95 100

2. In a furnace, a combined lining at the rear side of the furnace and inclined diaphragm provided with openings extending longitudinally through them, and connected with the 5 ash-pit below the grate, and having one or more steam-jets protruding into said openings at the sides or ends, substantially as and for the purpose set forth.
3. In a furnace, the combination of a lining, 10 F, and diaphragm G, having longitudinally-arranged openings *f g*, connected to the atmosphere by one or more openings, *h k*, into which steam-jets *i l* protrude, to draw in and force 15 hot air and steam into the ash-pit under the grate, substantially as shown and described.
4. In a furnace, the combination of the combined lining and diaphragm F G, having longitudinal openings *f g*, and openings *m*, with the steam-jets *i l*, and openings *h k* through the water-legs of the furnace for forcing a combined steam and hot-air blast into the ash-pit under the grate, all arranged substantially as shown and set forth. 20

In testimony whereof I affix my signature in presence of two witnesses.

ALFRED BERNEY.

Witnesses:

S. N. BERNEY,

ROBT. GERARD.
